CLAIM

The ornamental design for a mirror extension arm for a wide-load truck, as shown and described.

DESCRIPTION

FIG. 1 is an enlarged top-front-left perspective view of a mirror extension arm for a wide-load truck showing my new design;

FIG. 2 is an enlarged bottom-rear-left perspective view thereof;

FIG. 3 is a front elevation view thereof;

FIG. 4 is a rear elevation view thereof;

FIG. 5 is an enlarged left elevation view thereof;

FIG. 6 is an enlarged right elevation view thereof;

FIG. 7 a top plan view thereof; and,

FIG. 8 a bottom plan view thereof.

The broken lines illustrate portions of the mirror extension arm for a wide-load truck which form no part of the claimed design.

1 Claim, 8 Drawing Sheets
